ATTORNEY

UNITED STATES PATENT OFFICE.

FRANZ EICHHORST, OF TREPTOW-ON-THE-REGA, GERMANY, ASSIGNOR OF ONE-HALF TO
FRITZ SCHMEKEL, OF MOUNT CLEMENS, MICHIGAN.

ROCKING-HORSE.

Application filed September 7, 1926. Serial No. 133,834.

This invention relates to amusement devices and more particularly to such devices adapted for use by children.

One of the objects of the invention is to provide a rocking horse capable of moving forward by the action of a rider.

Another object is in the provision of means whereby the horse may be steered in any desired direction.

10 A further aim is to provide a device which, while affording much enjoyment to a rider, at the same time provides a healthful exercise.

These and other objects, such as simple 15 construction, low cost of manufacture, etc., are accomplished by the novel combination and arrangement of parts, hereinafter described and illustrated in the accompanying illustration, forming an important part of 20 this disclosure, and in which:—

Figure 1 is a side elevational view of an embodiment of the invention.

Figure 2 is a plan view of the support.

In the drawing, the numeral 10 generally 25 designates a V-shaped frame to which is pivoted at its apex 11, by a vertical pintle 12, a cross-bar 13.

Extending downwardly from the center of 30 the bar 13, is a pair of vertical elongated lugs 14 at the lower end of which is secured a short axle rod 15 on which is rotatably mounted a wheel 16.

Passing through the arms of the frame 10 at their outer parallel ends 17 is a shaft 18 35 having a crank 19 formed centrally thereon, the shaft carrying a pair of wheels 20 at the ends.

Secured to the frame 10 near the rear thereof at 21, is a pair of angular inreaching supports 21' having openings in their 40 parallel upper ends.

Fixed to the frame on the opposite side of the center at 22 is a pair of parallel supports 22' having openings in their ends in 45 alignment with the openings in the supports 21.

Passing through these openings is a rod 23 on which is pivoted a flat plate 24, the 50 rod carrying at its outer ends a pair of pulleys 25.

Secured to the plate 24 is the body 26 of a toy horse large enough to accommodate a child, the horse having fixed thereon a sad-

dle 27 and two pair of brackets 28 in which are fixed pins 29 supporting straps 30 carrying stirrups 31 at their ends. 55

Secured to the hind legs 32 of the horse at their upper extremities is a pair of brackets 33 in which is pivoted at 34 a link 35, the lower end of which engages the 60 crank 19.

Passing through the head of the horse, at its mouth, is a rod 36 carrying at its ends a pair of pulleys 37 over which is trained a cord or reins 38 accessible to a rider, and 65 fixed in openings 39 in the ends of the bar 13, as shown in Figure 1.

In operation, a rider seated in the saddle 27 draws the reins 38 backwards, thus causing the body of the horse to tilt forwardly, 70 which action, because of the link 35, revolves the cranked shaft 18, moving the toy forwardly.

By slackening the reins and leaning slightly backward the rotation of the shaft 75 is obviously continued; repeated operation thus giving continued motion.

To steer the toy to the right or left, the corresponding side of the reins 38 is pulled taut, which, through the cord connection in 80 the openings 39 in the bar 13 will accomplish this purpose.

From the foregoing, it may be seen that a toy has been disclosed that will move forward by the action of a rider, is easily 85 steered by the reins and which affords a healthful outdoor exercise for youngsters.

Having thus described my invention, what I claim as new and desire to secure by Letters Patent, is:—

A rocking horse comprising a V-shaped frame, a cross-bar pivoted to said frame, said bar carrying a steering wheel, a cranked shaft journaled in the arms of said frame, a pair of wheels fixed on said shaft, a body 90 pivotally mounted on said frame, a link pivoted to said body, said link being pivotally connected to said cranked shaft, a plurality of pulleys mounted on said body and supports extending upwardly from said frame, 95 and reins trained over said pulleys and fixed to said cross-bar, by which the said horse is moved forwardly and steered. 100

In witness whereof I have signed my name to this specification.

FRANZ EICHHORST.
